UNITED STATES PATENT OFFICE.

ALFRED G. KINTZ, OF WALLINGFORD, CONNECTICUT, ASSIGNOR TO INTERNATIONAL SILVER COMPANY, OF MERIDEN, CONNECTICUT, A CORPORATION OF NEW JERSEY.

DESIGN FOR A DISH OR SIMILAR ARTICLE.

Application filed April 28, 1928. Serial No. 26,497. Term of patent 7 years.

To all whom it may concern:

Be it known that I, ALFRED G. KINTZ, a citizen of the United States, residing at Wallingford, county of New Haven, and State of Connecticut, have invented a new, original, and ornamental Design for a Dish or Similar Article, of which the following is a specification, reference being had to the accompanying drawing, forming a part thereof.

Fig. 1 is a plan view of a dish showing my new design, except that only a portion of the ornamentation upon the border is shown. The border ornamentation shown extends completely around the dish.

Fig. 2 is a side elevation of a portion of the dish.

I claim:

The ornamental design for a dish or similar article, as shown and described.

ALFRED G. KINTZ.
